COMPOUNDS OF THE DIAMINO-ACRIDINIUM SERIES AND PROCESS OF PREPARING THEM

Max Bockmühl and Otto Sievers, Frankfort-on-the-Main-Hochst, Germany, assignors to Winthrop Chemical Company, Inc., New York, N. Y., a corporation of New York

**No Drawing. Application April 17, 1936, Serial
No. 75,016. In Germany April 20, 1935**

7 Claims. (Cl. 260—279)

The present invention relates to compounds of the diamino-acridinium series and to a process of preparing them.

5 We have found that the compounds from 3,6-diamino-acridinium compounds and aliphatic, aliphatic-aromatic and hydroaromatic ketones described in U. S. Patent No. 2,044,892 of June 10 23, 1936, to Otto Sievers, may very readily be split up. Already after a short boiling with water the ketones begin to escape and when boiling is continued there is obtained an aqueous solution of the 3,6-diamino-acridinium hydroxides:

wherein **X** stands for alkyl or benzyl and **Y** for hydrogen or alkyl low in the series. These hydroxides may be transformed into the corresponding ethers by means of alcohols, phenols, alcoholates or phenolates, or into the corresponding acridinium salts by means of salts or acids. Dilute acids split up the ketones gradually when the compounds are allowed to stand at room temperature and very quickly when boiled. By applying calculated amounts of acid there may be obtained neutral, or if dibasic or polybasic acids or the salts thereof are used, acid acridinium compounds of the corresponding acids.

35 compounds of the corresponding acids.
Instead of the acids there may be used the salts thereof formed with the aid of readily volatile bases, for instance, ammonia, aniline, methylamine, dimethylaniline; there may also be used the acid amides, such as formamide or acetamide which, on boiling with water, yield the corresponding ammonium salts or amine salts, the acridinium hydroxides displacing the readily volatile amines. The latter pass over with the water vapor. The salt formation at the amino nitrogen is thus avoided, since the transformation only takes place until all of the acridinium hydroxides are converted into the acridinium salt whereas an excess of the amine salt remains dissolved in an unaltered condition. The re-

action, for instance, takes place according to the following scheme:

wherein R stands for any acid radical. Owing to the great variety of possible methods it is possible to obtain in a simple way and in an entirely pure form any desired acridinium compound, particularly also compounds which are very readily soluble and cannot be obtained by another method. There may also be obtained acridinium compounds of polybasic acids the other acid radicals of which still contain metals, for instance according to the following scheme:

The products thus obtained have very good disinfecting properties; they are especially distinguished by a good efficacy upon gonococci in the tissue and therefore are particularly to be used as disinfecting agents. 40

The following examples serve to illustrate the invention, but they are not intended to limit it thereto:

1. 65 grams of 3,6-diamino-10-methylacridiniumacetone compound are heated in a sodium chloride bath with 3 liters of water and a small

quantity of animal charcoal. The escaping acetone is distilled. Since the acridinium hydroxide obtained is very oxidizable a strong current of nitrogen is passed through the flask. When about 1200 cc. of liquid are distilled, the separation of acetone ceases. The whole is filtered into a measuring flask, made up to 2000 cc. and the air is displaced from the flask with the aid of nitrogen. In this state the solution is stable for 10 an unlimited time.

2. 500 cc. of the solution prepared as described in Example 1 are mixed with a solution of 8 grams of sodium metavanadate in 100 cc. of water. The 3,6-diamino-10-methylacridinium-vanadate is 15 precipitated from the solution which becomes strongly alkaline to phenolphthalein. It is a red-brown powder which dissolves in water in the proportion of 1:4000.

3. To a solution of 8 grams of potassium chloride in 100 cc. of water there are added 500 cc. of acridinium hydroxide solution prepared as described in Example 1. The 3,6-diamino-10-methylacridinium chloride precipitates with formation of free caustic potash solution in the form 25 of a brown-red powder. It dissolves in water in the proportion of 1:250.

4. 14 grams of 3,6-diamino-10-methylacridiniumacetone compounds are heated for 3 hours on a water bath with 400 cc. of water and 10 30 grams of quinic acid. A clear solution is obtained. Animal charcoal is added to the solution; the water is evaporated and the product is again dissolved with 150 cc. of hot water, filtered and made up to 200 cc. A solution of 10 per cent. 35 strength of the 3,6-diamino-10-methylacridinium-hexahydrotetraoxybenzoate is thus obtained from which this compound may easily be isolated. It forms a brick-red crystalline powder which is very readily soluble in water, readily 40 soluble in methyl alcohol and ethyl alcohol, sparingly soluble in acetone and completely insoluble in ether, ethyl acetate and benzene.

5. 10 grams of camphoric acid are dissolved in 400 cc. of water and 50 cc. of normal caustic soda 45 solution. 14 grams of 3,6-diamino-10-methylacridiniumacetone compound and a small quantity of animal charcoal are added to the solution. The whole is heated on the water-bath until the undesirable foaming has ceased; the solution is 50 then boiled for one hour and finally evaporated to dryness. It is then dissolved with 150 cc. of hot water, filtered and made up to 220 cc. The solution contains 10 per cent of the sodium salt of 3,6-diamino-10-methylacridiniumcam- 55 phoric acid compound which may be isolated in the usual manner. It is a yellow powder which is very readily soluble in water, readily soluble in methyl alcohol and ethyl alcohol, sparingly soluble in butanol, scarcely soluble in acetone and insoluble in ethyl acetate, benzene and ether. The compound corresponds with the following formula:

70 6. 14 grams of 3,6-diamino-10-methylacridiniumacetone compound are heated on the water-bath in an open vessel with 400 cc. of water and 10 grams of microcosmic salt (sodium ammonium 75 hydrogen phosphate). A clear solution is grad-

ually obtained, acetone and ammonia being evolved. It is evaporated to dryness, dissolved in a small amount of water, again evaporated, again dissolved with addition of animal charcoal, filtered and made up to 170 cc. A solution of 10 per cent. strength of 3,6-diamino-10-methylacridinium sodium phosphate of the formula:

is obtained.

7. 14 grams of 3,6-diamino-10-methylacridiniumacetone compound are evaporated in an open vessel with 400 cc. of water and 1.9 grams of ammonium fluoride; the residue is taken up with water, filtered with animal charcoal and made up to 240 cc. A solution of 5 per cent strength of 3,6-diamino-10-methylacridinium fluoride is obtained.

8. A mixture of 15 grams of 2,7-dimethyl-3,6-diamino-10-methylacridiniumacetone compound, 200 cc. of water and 7 grams of aniline hydrochloride is distilled with steam; as soon as neither aniline nor acetone passes over, the yellow solution is filtered with a small quantity of animal charcoal and cooled. The 2,7-dimethyl-3,6-diamino-10-methylacridinium chloride separates in a completely pure form.

9. 16 grams of 3,6-diamino-10-methylacridiniumcyclohexanone compound are boiled with 2 liters of water and 12 grams of para-oxybenzoic acid until the evolution of cyclo hexanone has ceased. The whole is mixed with animal charcoal and filtered. The 3,6-diamino-10-methylacridinium-para-oxybenzoate which crystallizes on cooling forms orange-red needles which dissolve in water in the proportion of 1:2500.

10. 14 grams of 3,6-diamino-10-methylacridiniumacetone compound are heated for 2 hours on the water-bath with 400 cc. of water, some animal charcoal and 11 grams of 2-pyridone-5-arsinic acid. The solution obtained is then evaporated to dryness in an open vessel. The residue is taken up with 100 cc. of hot water, the solution is filtered and cooled. The 3,6-diamino-10-methylacridinium-2'-pyridone-5'-arsinate crystallizes in the form of light-yellow needles which dissolve in water in the proportion of 1:50; they are insoluble in the usual organic solvents except in methyl alcohol and ethyl alcohol.

11. 140 grams of 3,6-diamino-10-methylacridiniumacetone compound are heated for 5 hours on the water-bath with 2 liters of water and 30 grams of acetamide. The whole passes into solution with evolution of acetone and ammonia. The solution is evaporated almost to dryness and the 3,6-diamino-10-methylacridiniumacetate is precipitated with acetone in the form of a red powder.

12. 6 grams of pyrocatechol are mixed with 100 cc. of the solution of 3,6-diamino-10-methylacridinium hydroxide prepared as described in Example 1. A thick yellow precipitate is obtained which is thoroughly stirred. 400 cc. of the solution of the base are then gradually added. The yellow precipitate is filtered with suction, washed with a small quantity of water and then with a mixture of equal parts of acetone and ether,

5 finally with ether and dried in the vacuum desiccator. The pyrocatechol ether of 3,6-diamino-10-methylacridinium hydroxide forms a yellow powder which is readily soluble in alcohol, sparingly soluble in water and insoluble in ether.

10 13. 15 grams of 3,6-diamino-10-allylacridinium acetone compound are boiled with 700 cc. of water as described in Example 1. As soon as about 350 cc. have distilled the solution is filtered and mixed with an alcoholic solution of 16 grams of tribromophenol. The red precipitate obtained is the 3,6-diamino-10-allylacridinium-tribromophenolate of the formula:

30 14. 15 grams of the 3,6-diamino-10-oxyethylacridinium-cyclohexanone compound are boiled with 200 cc. of water, nitrogen being passed through until complete dissolution has occurred. The solution evaporated to 100 cc. is filtered and mixed with a solution of 6 grams of pyrocatechol in 50 cc. of water. The 3,6-diamino-10-oxyethylacridinium-ortho-oxyphenolate separates in the form of a yellow precipitate. It has the formula:

55 15. 28 grams of the 3,6-diamino-10-methylacridiniumacetone compound are boiled for 3 hours in the reflux apparatus with 25 grams of benzyl alcohol. The 3,6-diamino-10-methylacridinium-benzyl alcoholate of the formula:

65 is precipitated in the form of a brown-yellow precipitate by means of ether.

70 16. 31 grams of the 2,7-dimethyl-3,6-diamino-10-methylacridiniumacetone compound are introduced, while stirring, into 500 cc. of pure water. On addition of 4.6 grams of formic acid of 100 per cent. strength a clear solution is obtained. It is boiled for 3 hours in an open vessel and then evaporated to dryness. The residue is dissolved in alcohol. The solution is clarified with animal

charcoal; on addition of ether the 2,7-dimethyl-3,6-diamino-10-methylacridinium formate is precipitated in the form of a red crystalline powder which is soluble to an almost unlimited extent in cold water to a solution having an extraordinarily strong green fluorescence.

10 17. 3.5 grams of glutamic acid are dissolved in 500 cc. of the solution of 3,6-diamino-10-methylacridinium hydroxide prepared as described in Example 1. After filtration the whole is made up to 375 cc. There is thus obtained a solution of 4 per cent. strength of 3,6-diamino-10-methylacridiniumglutamate of the formula:

If only 250 cc. of the solution of the acridinium hydroxide are used the mono-glutamate is obtained.

30 In this manner even the most sensitive acids may readily be transformed into their 3,6-diamino-10-alkylacridinium salts.

We claim:

1. The process which comprises heating with water a compound obtainable by causing a compound of the following general formula:

45 wherein R stands for a member of the group consisting of alkyl and benzyl, X stands for the anion of a strong mineral acid and both Y's stand for a member of the group consisting of hydrogen and lower alkyl, to act upon a compound selected from the group consisting of aliphatic, aliphatic-aromatic and hydroaromatic ketones in the presence of caustic alkali.

50 2. The process which comprises heating with water a compound obtainable by causing a compound of the following general formula:

wherein R stands for a member of the group consisting of alkyl and benzyl, X stands for the anion of a strong mineral acid and both Y's stand for a member of the group consisting of hydrogen and lower alkyl, to act upon a compound selected from the group consisting of aliphatic, aliphatic-aromatic and hydroaromatic ketones in the presence of caustic alkali, the heating process being performed in the presence of a compound selected from the group consisting of acids, acid salts, acid amides or salts of volatile bases.

70 3. The process which comprises heating with water the compound obtainable by causing the 3,6-diamino-10-methylacridinium chloride to act upon acetone in the presence of sodium hydroxide.

4. The process which comprises heating with

5

10

25

30

35

45

50

55

60

65

70

75

water in the presence of hexahydrotetrahydroxybenzoic acid the compound obtainable by causing the 3,6-diamino-10-methyl-acridinium chloride to act upon acetone in the presence of sodium hydroxide.

5. The process which comprises heating with water in the presence of camphoric acid the compound obtainable by causing 3,6-diamino-10-methyl-acridinium chloride to act upon acetone in the presence of sodium hydroxide.

10. The process which comprises heating with water in the presence of 2-pyridone-5-arsonic acid the compound obtainable by causing 3,6-diamino-10-methyl-acridinium chloride to act upon acetone in the presence of sodium hydroxide.

15. The process which comprises heating with

7. The compounds of the following formula:

wherein R stands for a radical of camphoric acid, said compounds being colored powders readily soluble in water, methyl alcohol and ethyl alcohol and difficultly soluble in other organic solvents.
